UNITED STATES PATENT OFFICE.

ULYSSES S. MOFFITT, OF LOS ANGELES, CALIFORNIA.

SWITCH-THROWING DEVICE.

1,111,313.

Specification of Letters Patent. Patented Sept. 22, 1914.

Application filed December 13, 1913. Serial No. 806,505.

To all whom it may concern:

Be it known that I, ULYSSES S. MOFFITT, a citizen of the United States, residing at Los Angeles, in the county of Los Angeles and State of California, have invented certain new and useful Improvements in Switch-Throwing Devices; and I do hereby declare the following to be a full, clear, and exact description of the invention, such as will enable others skilled in the art to which it appertains to make and use the same.

This invention comprehends improvements in switch throwing devices and relates more particularly to those of the type which are adapted to be carried by trolley cars and manually operated to open or close a switch.

One of the objects of the invention is to provide a switch throwing device which shall be of extremely simple construction, easy to operate and very reliable.

Another object of the invention is to provide a switch throwing device including a pair of wedge shaped shift blocks rigidly secured to rotatable and longitudinally movable shafts, said shafts being rotated from a main shaft and being shifted longitudinally by means of foot actuated levers.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

40 Figure 1 is a fragmentary side elevation partly in section, showing one end of a car and my switch throwing mechanism secured thereto, the mechanism being shown partly in elevation and partly in section. 45 Fig. 2 is a horizontal section taken on the plane of line 2—2 of Fig. 1, Fig. 3 is a vertical section taken on the plane of line 3—3 of Fig. 2, and Fig. 4 is a view of a portion of a track showing how the shift blocks are 50 positioned relative to the switch.

Referring in detail to the drawings by numerals, 5 designates as an entirety a portion of a car having a platform 6 and a dashboard 7. A rectangular frame 8 is se-

cured to the bottom of the car under the 55 platform 6 and serves as a bearing for the vertical shafts 9 and 10. These shafts project into openings 11 formed in the platform 6 and carry upon their lower ends below the lower frame bar, shift blocks 12. These 60 blocks are preferably made wedge shape having converging side faces 13 and are also formed with longitudinal bores 14 into which the shafts 9 and 10 project. Set screws 15 removably secure these shift blocks 65 to the shafts. A sprocket wheel 16 is rigidly secured to each of the shafts within the frame and is engaged on its underside by the expansive coil spring 17. These springs 70 encircle the shafts 9 and 10 and bear at their lower ends against the lower bar of the frame 8 and serve to hold said shafts normally in their elevated positions at which times the shift blocks are above the track rails 18.

A main operating shaft 19 is journaled through the platform 6 adjacent the dashboard 7 and through a bracket 20 secured to said dashboard. The shaft extends below the platform and has rigidly secured to its 80 lower end a sprocket wheel 21 around which a sprocket chain 22 runs, said chain also passing around the sprockets 16 on the shafts 9 and 10. The shaft 19 may be rotated by means of a handle 23. This handle carries 85 a catch 24 for engagement with a toothed quadrant 25 whereby the shaft may be locked against movement.

To provide for individually moving the shafts 9 and 10 downwardly so as to bring 90 the shift blocks 12 into operative position, I provide a pair of levers 26. These levers are pivoted at their inner ends to brackets 27 carried by the underside of the car and are connected at their forward ends to push 95 rods 28. The levers are normally disposed in a horizontal plane, converge toward one another as they approach their outer ends and are positioned above the sprocket chain 22. Each of the levers is formed with longitudinal slots 29 through which the rods 9 and 10 extend. When a car is approaching a switch, as indicated in Fig. 4, and it is desired to shift the switch rails 30 and 31 so that the car will continue in a straight 100 line, the shaft 9 is forced downwardly by means of the corresponding lever 26 so that one of the shift blocks will be brought into

engagement with the rail 30. The outer inclined face 13 of this shift block will tend to shift the switch rails 30 and 31 laterally by engaging the point of the switch rail 30 and this action may be assisted by rotating the shaft 19 so as to swing the point of the depressed shift block outwardly. Should a car be approaching the switch from the other direction, the shift block 10 on the right hand side of the car is depressed so as to engage the outer face of the rail 31 thus closing the switch and allowing the car to continue in a straight line.

From the foregoing description taken in connection with the accompanying drawings, it will be evident that I have provided a very simple and practical switch throwing mechanism which may be very easily operated.

While I have shown and described the preferred embodiment of my invention, it will be understood that minor changes in construction, combination and arrangement of parts may be made without departing from the scope and spirit of the invention as claimed.

Having thus described my invention, I claim:

The combination with a car, of a throwing device comprising a pair of vertical shafts mounted for longitudinal and rotational movement, a shift block secured to the lower end of each shaft, a pair of horizontal levers pivoted at one end and formed intermediate their ends with openings through which the shafts extend, means for forcing the free ends of said levers downwardly, a sprocket wheel secured to each of the shafts and engaging the underside of the levers, a main vertical shaft, a sprocket wheel secured to said shaft, a sprocket chain connecting said sprocket wheels, spring means for holding the first mentioned shafts normally in their elevated positions, and means for rotating the main shaft.

In testimony whereof I affix my signature in presence of two witnesses.

ULYSSES S. MOFFITT.

Witnesses:

COLEMAN A. CARPENTER,
DOCTOR Y. KENNADY.
